Primary Examiner — Doris Clark(74) *Attorney, Agent, or Firm* — Boyle Fredrickson, S.C.**CLAIM**

The ornamental design for a frame member, as shown and described.

DESCRIPTION

FIG. 1 is an isometric view of a frame member in accordance with the present invention;

FIG. 2 is an end view of the frame member of FIG. 1; and, FIG. 3 is a side elevational view of the frame member of FIG. 1.

The broken lines are for illustrative purposes only and form no part of the claimed design.
